CLAIM

The ornamental design for a display screen with graphical user interface, as shown and described.

DESCRIPTION

This application is related to U.S. Design patent application Ser. No. 29/710,584, U.S. Design patent application Ser. No. 29/710,585, entitled Transforming Scale Ring, all filed on Oct. 24, 2019, and all of the disclosures of which are herein incorporated by reference.

FIG. 1 is a front view of a display screen with graphical user interface according to a first embodiment of our new design; and,

FIG. 2 is a front view of a display screen with graphical user interface according to a second embodiment of our new design.

The dot-dash lines depict the display screen and form no part of the claimed design. The remaining broken lines showing portions of the graphical user interface form no part of the claimed design.
